UNITED STATES PATENT OFFICE.

CLARENCE A. SHALER, OF WAUPUN, WISCONSIN.

BURNER.

Application filed October 12, 1921. Serial No. 507,346.

To all whom it may concern:

Be it known that I, CLARENCE A. SHALER, a citizen of the United States, residing at Waupun, county of Dodge, and State of Wisconsin, have invented new and useful Improvements in Burners, of which the following is a specification.

This invention relates to burners for hydrocarbon, and is particularly directed to 10 kerosene burners.

Objects of this invention are to provide a burner which will produce a perfect mixture; to provide a burner so constructed that an adequate and proper amount of air is 15 ensured; to provide a burner which secures intimate mixing, at a plurality of points, of the air and fuel; to provide a burner which has a primary mixing operation and a secondary mixing operation; and to provide a 20 burner which will produce a substantially colorless or slightly bluish flame with no resulting fumes from unburnt material.

Further objects are to provide a burner which will produce a very stable flame; to 25 provide a burner which may be placed in a strong draft without danger of extinguishing the flame; and to provide a burner of such construction that external currents of air, altho directly striking the burner, will 30 at most merely aid in the rapidity of combustion.

Further objects are to provide a burner which may be formed from a comparatively simple casting, which is provided with adequate means for cleaning the burner from 35 any deposits that may occur; to provide means for draining the burner when it is desired, and to provide a burner with readily renewable parts, so that if any part becomes worn or damaged it may be quickly 40 and easily replaced.

An embodiment of the invention is shown in the accompanying drawing, in which

Figure 1 is a plan, partly in section, of 45 the burner.

Figure 2 is a vertical sectional elevation of the structure shown in Figure 1.

The burner comprises a body portion which may be formed from a single casting, 50 and is provided with a bottom wall 1 and top wall 2, and concentric inner and outer circular walls 3 and 4. A cavity 5 of annular contour is thereby provided between these walls. Both the upper wall 2 and outer wall 4 extend upwardly to provide 55 upper flanges 6. A baffle plate consisting of

a relatively small disc 7 centrally positioned above the upper wall is integrally joined to such flanges 6 by means of a pair of outwardly projecting tongues 8. The outer 60 wall 6, at one side, projects to form a cavity 9 into which an elbow joint 10 is screwed. From this elbow joint a supply pipe 11 extends transversely across the upper portion of the burner and above the connecting 65 tongues 8. This supply pipe is preferably downwardly turned as indicated at 12 upon the opposite side of the burner and extends from this point to a supply tank which contains the fuel under pressure. 70

A duct or passage way 13 extends downwardly from the interior of the cavity 5 and is provided with a relatively short upwardly projecting protecting flange or shoulder 14. The lower portion of this duct is threaded 75 and receives the neck 15 of the needle valve nozzle 16, such nozzle being provided with a very small opening at its upper end and with a control or hand wheel 17 at its lower end by which the flow of gas through the 80 minute opening may be readily controlled. Above the nozzle 16 a tube 18 is positioned with slight clearance between the upper end of the nozzle to the lower end of the tube. This tube may be cylindrical or have Ven- 85 turi shape and is positioned in a circular opening in a bracket 19, formed integrally with the body portion of the burner, and is retained in position by means of a set screw 20. It is to be noted that the tube 18 is 90 spaced a material distance from the inner wall 3 and is concentrically arranged with respect to such inner wall.

In order to facilitate the draining and cleaning of the burner when the supply of 95 fuel is cut off from the supply pipe 11, a drain pipe 21 is provided, such pipe being screwed into a threaded duct 22 communicating with the cavity 5 at any desired point. The lower end of the drain pipe is equipped 100 with a stop cock 23, which, of course, is closed during normal operation. A pair of removable plugs 24 and 25 are provided in the outer wall 4 of the burner and greatly facilitate the removal of any carbonized 105 material or collected sediment within the cavity 5.

The operation of the device is as follows: The fuel passing under pressure through the pipe 11, which latter is preferably loosely packed with asbestos 26, is partially or completely vaporized in such pipe, although the 110

direct flame is deflected by the tongues 8 and baffle plate 7 from contact with such pipe. The gas and any remaining liquid passed into the cavity 5 which is also heated by the flame which closely hugs the upper wall 2, and by the radiated heat from other portions of the burner. This gas is then further heated and the complete vaporization of the fuel is insured, the upwardly extending rib preventing any liquid that may remain in the cavity 5 from passing freely into the duct 13 and to the nozzle 16. This gas under pressure passes upwardly through the minute opening in the nozzle 16 and entrains air in the pipe 18, due to the high velocity of the upwardly passing stream of gas. The resulting mixture in the tube 18 is relatively rich and is projected upwardly at a high velocity against the baffle plate 7 to be uniformly spread by such plate. The outwardly passing sheet of thin film of rich mixture entrains further quantities of fresh air which pass upwardly between the tube 18 and the annular wall 3, and causes intimate mixing of the relatively rich mixture and incoming fresh air. This effect is further increased by the peculiar construction of burner, for it will be seen that the film of intimately mixed gas and air passing radially outwardly beneath the disk 7 is of constantly increasing cross sectional area. Consequently the effect of this is to produce a suction, inasmuch as the velocity will necessarily be retarded, as the same volume of gases flow out in given quantities across the sectional area, if supplied solely by that passing thru the tube 18. However, as this velocity is decreased, a suction occurs, and additional air is drawn into intimate contact with the outwardly passing film.

From actual experiments with this burner, it has been found that a practically colorless, or at most a slightly bluish flame, is produced, and that no objectional odors from any unburned particles result. It has also been found that the burner will operate efficiently, although subjected to a strong draft of air, for as will be seen that the air rushing across the upper surface of the burner will not blow out the flame, but at most will increase the velocity of upwardly passing gases.

It is also to be noted that the burner may be readily constructed cheaply and with a minimum amount of machine work, and that adequate means are provided for readily cleaning such burner.

I claim:

1. A hydrocarbon burner comprising the combination of a body portion subdivided into an upper cup-shaped open cavity and a lower annular cavity through which a tubular air passage extends to the upper cavity, a disk covering the central portion

of the upper cavity and supported from the side walls thereof in spaced relation thereto, a ring supported from the wall of the air passage, a tube adjustably supported by said ring in the air passage, a valved nozzle in communication with said lower cavity and arranged to discharge upwardly into the lower end of said tube, and a fuel supply pipe leading horizontally across the upper cavity and downwardly into the lower cavity.

2. A hydrocarbon burner comprising a metal body having an upper burner cavity and a lower vapor cavity, the latter provided with a central air passage therethrough leading to the upper cavity, a central baffle plate covering the portion of the upper cavity above said air passage, an open ended mixing tube supported in the air passage, a nozzle adapted to deliver fluid from the vapor cavity to the mixing tube, and a fuel supply duct extending across the upper cavity and communicating with the vapor cavity.

3. A hydrocarbon burner comprising a metal body having an upper burner cavity and a lower vapor cavity, the latter provided with a central air passage therethrough leading to the upper cavity, a central baffle plate covering the portion of the upper cavity above said air passage, an open ended mixing tube supported in the air passage, a nozzle adapted to deliver fluid from the vapor cavity to the mixing tube, and a fuel supply duct extending across the upper cavity and communicating with the vapor cavity, said metal body, disk and the walls of the air passage being formed integrally of cast metal, and said vapor cavity being provided with a valved drain aperture and normally plugged clean-out apertures.

4. In a hydrocarbon burner comprising the combination of a cast metal body having a vapor cavity, and a central air passage extending therethrough, a supply duct extending horizontally across the central portion of said body and communicating with said cavity, said body having a superposed burner cavity to which said air passage leads, interposed between the lower cavity and the supply duct and provided with a central baffle plate for directing fluid radially in the burner cavity, said burner cavity being open at the top on both sides of the supply duct between the baffle plate and its outer walls, a mixing tube in the air passage spaced from the side walls thereof, a nozzle arranged to discharge upwardly into the mixing tube, and connections for supplying fuel from the vapor cavity to said nozzle from a point substantially midway between the top and bottom of the vapor cavity.

5. A hydrocarbon burner comprising the combination of a body portion subdivided

into a burner cavity and a vapor cavity beneath said burner cavity and provided with a tubular air passage extending upwardly to the burner cavity, a disk like baffle plate disposed above said passage and spaced from the walls of said burner cavity, a pair of arms extending from the side walls of said cavity and supporting the baffle plate at opposite sides thereof, a tube adjustably supported in said air passage, a valve nozzle

in communication with the vapor cavity and arranged to discharge upwardly into said tube, and a fuel supply pipe leading horizontally across the burner cavity and downwardly into the vapor cavity, said baffle plate having its supporting arms disposed substantially vertically beneath said fuel supply pipe. 15
